UNITED STATES PATENT OFFICE.

ROBERT G. SEELHOFF, OF CHICAGO, ILLINOIS.

DESIGN FOR A VALANCE.

Application filed March 12, 1928. Serial No. 25,805. Term of patent 3½ years.

To all whom it may concern:

Be it known, that I, ROBERT G. SEELHOFF, a citizen of the United States, residing at Chicago, in the county of Cook and State of Illinois, have invented a new, original, and ornamental Design for a Valance, of which the following is a specification, reference being had to the accompanying drawing, in which a plan view of the valance is shown.

The detail illustration of the drawing depicts practically a unit of the design which is repeated throughout the extent of the valance.

I claim:—

The ornamental design for a valance, as shown and described.

In testimony whereof I affix my signature.

ROBERT G. SEELHOFF.
